UNITED STATES PATENT OFFICE.

MAX F. W. PLISKE, OF LAKEWOOD, OHIO.

HEATER.

No. 846,611.

Specification of Letters Patent.

Patented March 12, 1907.

Application filed June 21, 1906. Serial No. 322,734.

To all whom it may concern:

Be it known that I, MAX F. W. PLISKE, a citizen of the United States, residing at Lakewood, in the county of Cuyahoga and State of Ohio, have invented new and useful Improvements in Heaters, of which the following is a specification.

My invention relates to heating systems for automobiles and other vehicles; and the object is to provide a construction of this class by which the main exhaust from the engine is utilized as the heating medium.

Another object is to provide means whereby the heat may be easily and quickly turned on or off, provision being made that none of the foul products of combustion shall leak into the car.

With these objects in view my invention consists in the improvements pointed out in the following specification and claimed in the claims, reference being made to the accompanying drawings, in which—

Figure 1 is a plan view illustrating the application of the invention to an automobile. Fig. 2 is a plan view of the heater with its grating removed. Fig. 3 is a vertical section of the heater. Fig. 4 is a detail in perspective. Fig. 5 is a detail in section.

1 indicates the main exhaust-pipe, leading from the engine to the muffler 2, of the ordinary type.

3 is the inlet-pipe, leading from the exhaust 1 to the heater 4, and 5 is an outlet pipe leading from the heater 4 to the muffler 2, as shown. The heater 4 I have shown as square in shape and is composed of the outer and inner casings 6 and 7, of galvanized tin or other suitable material, having between them a layer of asbestos 7^a in order to insure a fireproof construction and also to hold the heat within said heater-box.

8 represents a series of heating-coils within the heater 4, and 9 is a grating-cover for said heater, fitting down flush with the floor 10 of the automobile or other car. The coils 8 are connected at one end to the outlet-pipe 5 and at the other end to the inlet-pipe 3 inside the wall of the heater 4 by means of the threaded sockets 11 and 12, having associated between them the valve-chamber 13. This valve-chamber 13 is preferably squared internally to provide firm seats for the valve-disks 14 and 15.

16 and 17 are hollow shanks extending from the disks 14 and 15, respectively, the shank 17 being smaller in diameter and

adapted to telescope into the shank 16. The shanks 16 and 17 are provided with slots 18 and 19, respectively, registering between themselves to form a single slot, 60 through which the valve-rod 20 is adapted to project and be held from coming out by means of the nuts 21 and 22 thereon.

23 is a stuffing-box having therein the packing 24 to secure against leakage from 65 the valve-chamber, and 25 is a cap attached to said stuffing-box by screws 26 and provided with a central slot, through which the valve-rod 20 reciprocates to open and close the valve. 70

27 is a spiral spring held about the shanks 16 and 17 and operating to hold the disks 14 and 15 firmly upon their seats at all times. Midway between the inlet-pipe 3 and the outlet-pipe 5, through the wall of the heater 4, 75 are arranged the slots 28, and opposite said slots on the inside of said wall are rotatably mounted the blades 29 on the pin 30, the said blades being adapted to register with the said slots 28. 80

31 is a foot-lever pivotally mounted on the pin 30 to the rear of the blades 29 and connected to said blades by means of the pin 32.

33 and 34 are connecting-rods pivotally connected at one end to the free end of the 85 valve-rods 20, the rod 33 being pivotally connected at its other end to the end of the foot-lever 31 below the pivot 30 by the pin 35 and the rod 34 being pivotally connected at its other end to said lever above pivot 30 by the 90 pin 32, connecting said lever to the blades 29.

The operation of my device is as follows: Taking the heater in the closed position, to open the same the foot is applied to lever 31, moving it forward and simultaneously drawing the valve-disks 14 and 15 of both inlet and outlet valve from off their seats, thus allowing the hot exhaust-vapors to be forced into the coils 8 by means of the back kick or back pressure following each explosion of the engine. Simultaneously with the opening of the inlet and outlet valves the blades 29 will be moved from the slots 28, thus allowing fresh air to enter the heater to be heated by the coils 8 and be thrown out through the 105 grating 9.

Should either of the valve-disks leak when the valve is closed the pressure thus created within the valve-chamber will force the opposite disk more firmly than ever upon its 110 seat, and should both disks of the inlet-valve leak the outlet-valve will still prevent a cir-

ulation and the hot vapors having entered the coils will become cold in a short time.

Having thus described my invention, what I claim is—

- 5 1. In a device of the character described, for utilizing the exhaust of an engine, a heating-box, heating-coils arranged therein, an inlet-pipe leading from said exhaust to said coils, a valve in said inlet, an outlet-pipe leading from said coils, a valve in said outlet, an air-valve in said heating-box and means for simultaneously operating the said inlet, outlet and air valves, substantially as described.
- 10 2. In a device of the character described, for utilizing the exhaust of an engine, a heating-box, heating-coils arranged therein, an inlet-pipe leading from said exhaust to said coils, a valve in said inlet, an outlet-pipe leading from said coils, a valve in said outlet, an air-valve in said heating-box and means for simultaneously operating the said inlet, outlet and air valves, substantially as described.
- 15 3. In a device of the character described, for utilizing the exhaust of an engine, a heating-

box, heating-coils arranged therein, an inlet-pipe leading from said exhaust and connected to one end of said coils, a valve in said inlet, an outlet-pipe connected to and leading from the other end of said coils, a valve in said outlet, an air-valve in the wall of said heating-box, and means for simultaneously operating said inlet, outlet and air valves, substantially as described. 25

In testimony whereof I have signed my name to this specification in the presence of two subscribing witnesses.

MAX F. W. PLISKE.
